UNITED STATES PATENT OFFICE.

HARRIS HULEN, OF KANSAS CITY, MISSOURI, AND CHARLES F. BROWN, OF SOUTH RIDGE, KANSAS.

BUILDING STRUCTURE OR SILO.

1,168,886.

Specification of Letters Patent. Patented Jan. 18, 1916.

Application filed December 7, 1914. Serial No. 875,969.

To all whom it may concern:

Be it known that we, HARRIS HULEN and CHARLES F. BROWN, citizens of the United States of America, and residents, respectively, of Kansas City, in the county of Jackson and State of Missouri, and South Ridge, in the county of Johnson and State of Kansas, have invented certain new and useful Improvements in Building Structures or Silos; and we do hereby declare that the following is a full, clear, and exact description of the invention, such as will enable others to make and use the same, reference being had to the accompanying drawings, forming a part of this specification.

The invention relates to building structures, for the reception of ensilage, the objects of the invention being, first, to combine in the structure a series of interchangeable units, the units being self-aligned, when brought together; second, to overcome outward pressure upon the walls of the structure; third, to enable tension to be instantly applied to the securing bands of the structure; fourth, to provide anti-friction bearings or wear plates at the junction of the units of the structure.

The invention consists in the novel construction and combination of parts, such as will be first fully described and then specifically pointed out in the claims.

In the drawings: Figure 1 is a front view, in elevation, of the building structure, embodying the invention, a portion only of the outer covering being shown. Fig. 2. is a horizontal sectional view, taken on the line x, x , in Fig. 1. Fig. 3. is an isometric view of broken portions of adjacent structural units, parts of the standards in each unit being broken away to show the alining strip. Fig. 4. is a horizontal, sectional view, taken through the door section and upon the line y, y , in Fig. 2. Fig. 5. is a detail view of the anti-friction or warping plate for the securing bands. Fig. 6. is a detail view of a portion of the lower, halved end of a standard and a connecting bar. Fig. 7. is a detail sectional view, enlarged of the lug for securing the ends of the wire cables showing the openings for the passage of the bolts and the securing and adjusting nuts.

Similar numerals of reference indicate corresponding parts in all the figures of the drawings.

55 The building structure or silo for the pur-

poses intended is preferably circular in form, and in construction the entire frame is composed of a series of independent, upright frames or structural units 10. These units or frames 10 are made preferably of the same height and width, each unit or frame consisting of upright standards 12, 12, arranged the requisite distance apart and in a parallel position. These uprights may consist of the ordinary 2x4 dimension lumber, the widest surfaces being placed opposite each other. The lower ends of the standards 12, 12, from the lines of the inner surfaces are cut away or halved at 13.

14 indicates the transverse connecting or stay bars, for connecting the standards 12, 12, of each frame or structural unit with each other. These bars are as shown of corresponding length, and proportioned in length to the desired width of the frame or structural unit, and are curved in the arc of a circle the degree of curvature being that obtained from the central point within the circle formed by the assembled units in the structure, as shown in Fig. 2. In the inner surfaces of the standards 12 are cut the notches 15, which are of the same depth as the halved portion 13, at the lower ends of the standards. These notches 15 are made at short distances from each other in the standards, and in series from the lower to the upper ends of said standards. The ends of the transverse connecting bars 14 are inserted within the notches 15, in the inner surfaces of the standards, which notches are made of slightly less size than the said ends of the bars 14, hence the bars are wedged within the notches and held firmly thereby. The ends of the lower bars 14 are then fitted within the halved lower ends of the standards 12, thereby forming the single frame or structural unit of the structure. The outer surfaces of these bars 14 are grooved at 16, in the direction of the standards, and the groove continued across on the alined surfaces of said standards. In the outer surfaces of each standard 12 is a groove 17, extending the length thereof, the lines of the sides of which groove are equi-distant from the forward and rear surfaces of the standard.

18 indicates a slip tongue which holds the standards 12 in alinement, and also closes the joint between standards in adjacent frames, the depth of the groove in the

standards being about one-half the thickness of the standard, and the slip tongue 18 being about twice the width of the groove, hence the portions of the tongue are adapted to fit within the grooves of adjacent standards of the separate frames.

One of the frames or structural units which is designed for use in obtaining entrance to and exit from the structure, is provided with vertical bars 19, arranged approximately equi-distant from the standards 12, 12 of the frame or structural unit 10, so as to afford door openings 20, in vertical series, the ends of each bar being secured 10 to the respective upper and lower surfaces of the adjacent connecting bars 14, the doors 21 being fitted within the openings 20, and hinged, as further described.

In the assemblage of the frames or structural units 10, to form the building or silo, the frames 10 are arranged in the direction of the lines of a circle, and the standards 12, of each frame, arranged in position so that the grooves 17, in each standard, are 20 opposed to each other. When in this position, the requisite number of frames or structural units are in position to make the circle complete, and a warping plate 22, having a curved depression 23, is placed 25 across the joint between the adjacent standards 12, of each structural frame or unit, the depression 23 being inserted within the groove 16, in the forward surfaces of the standards, the plate being secured at their 30 ends to the adjacent standards 12, in each frame, by the nails or screws 22.

Extending circumferentially to the assembled frames or structural units 10, within the grooves 16, are wire cables 25, the 40 ends of said cables being secured to the eyes 26, of screw bolts 27, these bolts being inserted loosely through the respective upper and lower openings 28 and 29, (see Fig. 7) of the lugs 30. The outer end portions of 45 the bolts are screw-threaded, and upon said ends of the bolts, and bearing against the ends of said lugs 30 are adjusting screw threaded nuts 31. These cables are employed in number equal to the number of transverse bars 14, and the nuts 31 being 50 tightened, the tension on the cables draws the frames 10 composing the units firmly together, the cables are warped within the grooves or depressions 23, in the plate 22, and hence, instead of passing over the angular surfaces of the standards are warped 55 within the grooves of the plate and obtain less friction when stress is applied to the cables.

60 The inner lining 32, of the structure or silo, is composed of vertically positioned boards 33, which are narrow in width, and provided with tongues 34, upon one longitudinal surface, and grooves 35 upon the other longitudinal surface. These boards

are positioned on the inner surfaces of the respective frames 10, and the tongue on one board matched with the groove of an adjacent board. The first board is secured in any suitable manner, at a point opposite the inner surface of the standard 12, forming the side of the door opening 20, and the other boards joined together in the direction of the inner circumference of the structure or silo, the lining boards, which are positioned in the direction of the strip 19, forming the opposite side to the door opening 20, terminating opposite said strips 19, hence the door 21 closes past the line of the surface of such board, which board is secured from movement by suitable nails or screws. The doors 21 are now hinged at 36 to the inner surface of the board 33, forming a part of the lining of the structure and opposite the standard 12, of the frame having the door opening 20, the door being of ordinary construction. The outer covering 38 is composed of matched boards, and which are placed upon the outer surfaces of the frames in the same manner as described 80 of the inner lining 32. An air chamber is thereby formed between the outer covering 38 and the inner lining 32. The building structure thus completed, requires no other fastenings than are herein stated, and hence 90 the structure, when contraction may take place, is unrestricted, the contraction being readily taken up by the wire bands 25.

Owing to the nature of ensilage, the lining 32 is subject to outward pressure, and this 100 pressure is overcome by the tension applied to the flexible cables or bands 25, through the adjusting and fastening devices 30 and 31, access to which is readily obtained by means of the horizontal rods 37, secured at 105 their ends to the strips or jambs 19, on the side of the door openings 20, and the standards 12, these rods forming a ladder for ascending from the ground to the upper portion of the silo. The outer covering 38, 110 to the structure before referred to, extends to the standards 12 at the respective right and left hand portions of the independent frame having the door openings 20 and the horizontal rods 37, as seen in Fig. 1.

115 The advantage which we obtain over the other forms of silos made from assembled frames, is in depressed wire bands or cables, which encircle the frames concentrically within continuous horizontal grooves in the 120 outer surface of the entire frame in line with the connecting segment bars of the independent frames, hence no one of the assembled frames can be displaced from its vertical position with an adjacent frame, the 125 cable or band bearing upon the upper and lower surfaces of the grooves thereby acting in a simple and inexpensive manner as a brace to each frame, so that they are held rigid and the silo structure moved if desired 130.

from one location to another. Furthermore the bands or cables are within the grooves close in position to each of the vertical slip tongues 18, in the grooves 17, of the standards 5 12, and draw these parts together effectively so as to exclude moisture, which moisture has a tendency to swell the slip tongues and open the joints.

An outer covering may be placed upon 10 the frame of the silo without interference with the bands or cables which is not permissible in other silos, and is new in the state of the art.

Hitherto it has not been possible to secure 15 the standards of adjacent independent frames with the ordinary external bands and permit the covering or boards to be laid over the bands, hence our devised wear plates permit the accomplishment of this result, and secure one standard of one frame 20 to an adjacent standard of an adjacent independent frame. The inner projection of the wear plate extends within the alined 25 grooves of these adjacent standards and when in position prevents sagging of these independent sections of the entire frame of the structure.

In order to make our securing bands or 30 cables effective for the purpose above mentioned, the securing lugs as seen are arranged in position at the door openings, and in rows, one above another. The invention permits the independent frames to be assembled interchangeably, and may also be 35 reversed if desired in position, and as a further advantage do not require to be bolted together.

The silo is ordinarily mounted upon a 40 concrete base (not shown), and secured thereto in any desired manner.

For rapid construction, the improved silo 45 is of great value, the parts being transported in a knock-down condition and erected at the desired place. The advantages of the structural units are such that the capacity of the silo may be increased circumferentially by the increasing of the 50 length of the curved connecting bars 14, with such other modifications employed as are within the scope of the appended claims.

Having fully described my invention, what I now claim as new and desire to secure by Letters Patent is:

1. In a building structure of the character described, a circular frame composed 55 of a series of independent frames each composed of vertical standards and transverse segment bars connecting one standard with another, said structure having horizontal grooves in the outer surface of said segment 60 bars, and flexible cables or bands within said grooves and lying below the plane of the outer surface of the circular frame, and means for applying tension to the ends of 65 said bands or cables.

2. In a building structure or silo, a circular frame composed of a series of independent upright frames, each independent frame having parallel standards, and segment bars secured at their ends to the respective standards, said circular frame having horizontal concentric grooves extending below the alined surfaces of the standards, and warping plates having depressed portions extending from one standard of an 75 independent frame to another standard of an adjacent frame in contiguity, and within 80 said grooves.

3. In a building structure or silo the combination with a circular frame composed of 85 a series of independent upright frames, each independent frame having parallel standards, and segment bars secured at their ends to the respective standards, said standards having vertical grooves in their opposing surfaces and a slip tongue within said 90 grooves, said circular frame having concentric grooves in the outer surface of the frame, and flexible cables within said grooves lying below the plane of the outer 95 surface of the frame and adjacent the said slip tongues, and adjustable connecting devices connected with the end portions of said flexible cables.

HARRIS HULEN.
